[57] CLAIM

The ornamental design for a lid for a refuse container, substantially as shown and described.

DESCRIPTION

FIG. 1 is a perspective view of a lid for a refuse container showing my new design;

FIG. 2 is a rear elevation view thereof;

FIG. 3 is a top plan view thereof;

FIG. 4 is a side elevation view thereof;

FIG. 5 is a front elevation view thereof;

FIG. 6 is a bottom plan view thereof;

FIG. 7 is a perspective view of a second embodiment of the lid for a refuse container;

FIG. 8 is a rear elevation view of FIG. 7;

FIG. 9 is a top plan view of FIG. 7;

FIG. 10 is a side elevation view of FIG. 7;

FIG. 11 is a front elevation view of FIG. 7; and

FIG. 12 is a bottom plan view of FIG. 7.

*Fig. 2.**Fig. 4.**Fig. 3.**Fig. 5.**Fig. 7**Fig. 12*

*Fig. 8**Fig. 10**Fig. 9**Fig. 11*
